UNITED STATES PATENT OFFICE.

ALBERT A. LONGAKER, OF CHAMBERSBURG, PENNSYLVANIA, ASSIGNOR TO CHAMBERSBURG ENGINEERING COMPANY, OF CHAMBERSBURG, PENNSYLVANIA, A CORPORATION OF PENNSYLVANIA.

WHEEL-PRESS.

1,091,458.

Specification of Letters Patent. Patented Mar. 24, 1914.

Application filed July 1, 1913. Serial No. 776,851.

To all whom it may concern:

Be it known that I, ALBERT A. LONGAKER, a citizen of the United States, and a resident of Chambersburg, in the county of Franklin and State of Pennsylvania, have made certain new and useful Improvements in Wheel-Presses, of which the following is a specification.

My invention relates to improvements in presses for mounting wheels upon or demounting them from an axle, and the object of my invention is to furnish a press for this purpose so arranged that the wheels and axle may be brought to it upon one side and after being operated upon can be removed from the other side, and which will have but two beams, both fixed, viz: a resistance beam and a cylinder beam.

In my invention I make use of a cylinder beam of the usual construction which carries the usual pump, valves and conduits for generating and controlling the hydraulic pressure necessary to operate the piston or ram in the cylinder carried by the beam, and I furnish a novel form of fixed C shaped resistance beam as hereinafter fully described.

In the accompanying drawings which form part of this specification and in which similar letters of reference refer to similar parts throughout the several views:— Figure 1, is a side elevation of my wheel press the frame of the resistance beam being formed in one casting: Fig. 2, a similar view the casting of the resistance beam being made in several pieces bolted together: Fig. 3, an end elevation of the distance piece 14: Fig. 4, an end elevation of the sleeve 16: Fig. 5, a side elevation of stop 11.

1 is the cylinder beam carrying the usual pump 2, a suitable means 3 for driving the pump, and connections from the pump to the cylinder which carries the ram 4. All of these parts are so well known that detailed description of them will be unnecessary here.

5 is the resistance beam which is C shaped and which is tied to the cylinder beam by rods or bolts 6 as shown in Fig. 1, or which 50 may be formed of several pieces, as 7—8—9, which are bolted together and to the cylinder beam as shown in Fig. 2. The resistance beam is furnished with a stop holder 10 which carries a removable stop 11, the stop

holder being furnished with a cavity 20 55 back of the stop to receive the end of an axle when the press is being used to force the left hand wheel upon it.

12 is a gap in the right hand or inner end of the resistance beam which carries a removable stop 13 which forms the abutment for the distance piece 14, which is carried upon a jib crane 15 carried by the resistance beam. This stop is used only in demounting 60 wheels.

16 is a sleeve, carried by a trolley 17 on a jib crane 18 carried by cylinder beam 1, which is engaged by the ram 4 to mount the right hand wheel upon an axle.

19 are wheel trucks of usual construction 70 for carrying wheels while being mounted upon or demounted from their axle.

The axle carrying the wheels to be mounted is rolled into the machine from either side, the distance piece 14 being 75 swung out of the way and the stop 11 being in place in its holder. The wheels rest upon the trucks 19 and the sleeve 16 is in position against ram 4 as shown in Figs. 1 and 2. The ram 4 is now advanced and the 80 sleeve 16 engages the outer face of the right hand wheel hub and pushes it on to its seat or fit upon the axle. The stop 11 is now removed and a further movement of ram 4 will push the axle into the left hand wheel 85 a proper distance. It might be feasible to remove the stop 11 in the first place and to push both wheels on their seats simultaneously the faces of the stop holder 10 and stop 13 acting as a gage for the tread of the 90 wheels.

It will be understood that during the operation of seating the wheels upon the axle the crane 15 is swung to one side so as to remove the distance piece 14 from the 95 path of the axle. When the distance piece is so removed the wheels and axle may be placed in or removed from either side of the machine. To demount a wheel the stop 11 is removed, the crane 15 is swung around so as 100 to bring the inner end of distance piece 14 against the inner end of the gap in the center resistance beam, or the stop 13 carried thereby, and the crane 18 carrying the sleeve 16, which is only used in mounting the right 105 hand wheel on the axle, is swung outward so as to move the sleeve 16 away from the end and to one side of the ram. The axle

carrying the wheel is now placed in the machine, the inner end of the hub of the right hand wheel resting against the outer, or right hand, end of the distance piece 14 5 and the ram 4 is advanced until it engages the right hand end of the axle to push it out of the wheel. The axle is now turned end for end and the same operation is gone through with and thus both wheels are successively removed.

21 is a pivoted carrier, carried by the casting of resistance beam 5, upon which the axle rests and which supports the axle and wheels while turning them end for end 15 in the machine.

In Fig. 1 the resistance beam is shown formed in a single casting. In Fig. 2 it is shown formed of three pieces 7—8—9, the piece 7 being bolted to the left hand ends of 20 pieces 8 and 9 and the right hand ends of these pieces being securely attached to cylinder beam 1.

My aim, which is to furnish an end resistance beam which will permit wheels to be either mounted upon or demounted from 25 their axles and which will be so constructed that the axle and wheels may be introduced upon one side and removed from the other side of the machine, may be accomplished by constructions other than those shown, I do not, therefore, desire to confine myself to any particular construction of this part except as required by the scope of the claims.

Having thus described my invention I 35 claim as new and desire to secure by Letters Patent:—

1. In a wheel press, in combination, a stationary beam, a ram carried by said beam, means for operating said ram, a stationary 40 end resistance beam furnished with a stop adapted to receive the end of an axle and to engage the hub of a wheel carried thereby, and a stationary through gapped stop

located between said ram carrying beam and said end beam adapted to engage the hub of a wheel carried by the other end of the axle, said ram and stops being all in substantially axial alinement.

2. In a wheel press, in combination, a ram and means for operating the same, a stationary cylinder beam carrying said ram, a stationary resistance beam having at its outer end a stop holder adapted to interiorly receive an end of an axle and to engage the hub of a wheel carried by said axle and having at its inner end a through gapped stop adapted to engage the hub of another wheel carried by said axle, said ram, through gapped stop, and stop holder being all in axial alinement, and a removable stop carried by said stop holder.

3. In a wheel press, in combination, a cylinder beam, a ram carried by said beam, means for operating said ram, and a combined end and center resistance beam, the latter being furnished with a through gap for the axle and the former with an adjustable stop, said stop, gap and ram being all in axial alinement, and said beams being immovably secured one to the other.

4. In a wheel press, in combination, a cylinder beam, a ram carried by said beam, means for operating said ram, a stationary resistance beam carrying a stationary through gapped stop intermediate of said beams, said stops and ram being in substantially axial alinement, and a revoluble axle support, pivotally carried by said through gapped stop, for permitting said axle to be turned end for end without removal from the press.

ALBERT A. LONGAKER.
